UNITED STATES PATENT OFFICE.

JAMES G. COWLES, OF MOUNT VERNON, MICHIGAN.

HORSESHOE.

SPECIFICATION forming part of Letters Patent No. 247,538, dated September 27, 1881.

Application filed January 13, 1881. (No model.)

To all whom it may concern:

Be it known that I, JAMES G. COWLES, of Mount Vernon, Macomb county, Michigan, have invented an Improvement in Horseshoes, 5 of which the following is a specification.

The nature of this invention relates to certain new and useful improvements in the construction of horseshoes; and the invention consists in the peculiar construction, arrangement, 10 and various combinations, all as more fully hereinafter set forth.

Figure 1 is a top perspective. Fig. 2 is a perspective of the plate removed. Fig. 3 is a bottom perspective. Fig. 4 is a vertical central longitudinal section, with adjustable calks removed.

In the accompanying drawings, which form a part of this specification, A represents a horseshoe of the ordinary construction, which may 20 be provided, if desired, with the toe-calk a. At the heel of this shoe I rigidly secure by any of the known means the bar B upon the under face of the shoe. Said means may consist in welding, as shown in Figs. 1 and 3, or 25 by screws or rivets, and the lower face of the bar B should be preferably wedge-shaped in cross-section. Ordinarily these bars are placed at the heel of the shoe, but on the upper face, and when such shoes are in use they are a detriment rather than an advantage, as they come 30 directly under the heel of the frog, causing the horse, in many instances, to injure or lame himself, by reason of the violent concussion of the frog upon the bar. With the bar placed upon 35 the under face of the shoe it not only affords a support for the heel, keeping the foot in the natural position in walking or trotting, but also allows of a free expansion of the frog, bringing no undue strain upon the ankle.

40 C is a plate, of the general form shown, provided upon its rear end with studs c. When this plate is in place these studs or spurs rest upon the top of the bar B, and the opposite end is secured to place by a proper screw, d. 45 This plate is employed for various reasons, the greater ones being that it protects the frog of the horse wearing it, prevents "balling-up" in winter, and stone-bruises. To this plate C, I secure a weight, D, of the desired size, by means 50 of a proper screw, e; and it is evident that the

weight can be applied to that portion of the shoe as circumstances may require by simply tapping a hole through the plate at the desired point. By this manner of construction the weights are inclosed between the hoof and the 55 plate C, avoiding the danger of their flying off, as when attached to the shoe on the outside, or, when applied as toe-weights, from being knocked off in "forging," while it does not interfere with the action of the horse or come in 60 contact with any portion of his foot.

E represents a bar heel-calk, and F a toe-calk, both of which are removably secured to place—the former to the bar B and the latter to the plate C. The toe-calk F in the drawings is shown as set back from the toe of the shoe; but it is obvious that the same can be placed at the point where it will be of the greater advantage to the horse.

By this construction and arrangement of 70 parts I provide removable calks, which can be readily removed, sharpened, and replaced without removing the shoe. I provide a plate for protecting the frog of the foot from being injured, and which can readily be weighted, if 75 desired; and I also provide a means of support for the horse's heel, and all of these points are sought after, particularly by owners of fast stock.

What I claim as my invention is—

1. In a horseshoe provided with a plate, C, and in combination therewith, the detachable weight D, substantially as described.

2. In combination with a horseshoe, the detachable plate C, having on one side a detachable 85 calk and on the other side a detachable weight, substantially as described.

3. In a horseshoe, and in combination with the bar B at the heel thereof, the detachable plate C, having fastening-studs c c, substantially as specified.

4. The detachable plate C, provided with the detachable weight D and pivoted fastening-studs c c, in combination with the heel-bar B of the shoe A, substantially as described.

JAMES G. COWLES.
